MATERIAL FEEDING TOOL FOR A SAW TABLE

Irwin W. Littlefield, San Jose, Calif.

Application May 19, 1958, Serial No. 50,966

Term of patent 14 years

(Cl. D93—4)

Fig. 1 is a top perspective view of a material feeding tool for a saw table showing my new design;
Fig. 2 is a side elevational view thereof;
Fig. 3 is a bottom plan view thereof;
Fig. 4 is a left end elevational view of Fig. 3; and
Fig. 5 is a right end elevational view of Fig. 3.

I claim:
The ornamental design for a material feeding tool for a saw table, substantially as shown.
